COLONIC-VAGINAL IRRIGATOR

Filed March 14, 1952

UNITED STATES PATENT OFFICE

2,644,451

COLONIC-VAGINAL IRRIGATOR

Edward Sokolik, New Brighton, Minn.

Application March 14, 1952, Serial No. 276,480

8 Claims. (Cl. 128—239)

1

My present invention relates to an improved irrigator for colonic or vaginal therapy and the principal object of the invention is to provide an irrigator that is sanitary and convenient in its application;

Another object is to provide an irrigator, whereby the liquid supply hose is used in a depending position and kept out of the flush bowl, and thereby contamination and kinking thereof prevented and the liquid flow facilitated;

Still another object is to provide a rectal nozzle that is self retainable and that is provided with non-cloggable discharge orifices, and

A further object is to provide a vaginal nozzle that is provided with longitudinally extending and radially projected ridges, whereby the vagina is distended and the irrigating liquid caused to flow in channels between the ridges.

These and other objects and advantages will be apparent as the description progresses.

Invention resides in the structure, arrangement, combination and shape.

In the accompanying drawings, which are a part of the disclosure:

Fig. 1 illustrates a plan view of the device with a portion shown in section.

Fig. 2 illustrates a longitudinal section of a vaginal nozzle on line 2—2, Figure 3.

Fig. 3 illustrates a cross-section on line 3—3, Figure 2.

Fig. 4 illustrates a cross-section on line 4—4, Figure 1.

In the embodiment of the invention as shown in Fig. 1 in combination with a flexible tubular conduit 5 connected to a liquid supply, which as shown is a rubber pouch 6, is a colonic irrigator 7. It is, as shown, a one-piece body-portion 8 of suitable material such as plastic, rubber, glass and the like. This body-portion 8 is comprised of an intermediate connecting-portion 9, a nozzle-portion 10 provided at one end of the connecting-portion 9 in a manner so that, in use, it is uprightly disposed, and a handle-portion 11 provided at the other end of the connecting-portion 9 in a manner so that, in use, it is sloping from the free end 12 thereof to the connected end thereof to prevent the flushing liquid running up along the handle and thereby preventing contaminating said handle 11. The nozzle 10 and/or the handle 11 may be provided with screw-threaded or other connecting means 18 at connecting ends thereof, adapted to connect with complementary connecting means 18 formed in the connecting-portion 9 and thereby be separable for interchanging or cleaning the nozzle 10 and for using the irrigator

2

when said handle 11 is not desired for any reason.

An improved feature of the connecting-portion 9 is the nubbin 13 formed on the underside of said connecting-portion 9 to do away with the conventional elbow curve along which the flush liquid flows onto the handle thereof, and to afford a surface for the flush liquid to flow down upon, instead of flowing along an elbow onto the handle. By this new mode of flow, which avoids the handle-portion 11, said handle-portion is not contaminated and is kept sanitary. This nubbin 13 may be variously shaped and is the lowest portion of the connecting-portion 9 and is below the connecting end of the handle-portion 11.

Improvement in the nozzle-portion 10 lies in that it has its connecting end 14 annularly enlarged at two adjacent points and constricted therebetween to form a neck, adapted to be engaged by the sphincter. A further improvement is in that it has its free end 15 annularly enlarged to provide ample girth in which to form radially and laterally arranged counter-sunk clog resistant liquid discharging orifices 16. Orifices not counter-sunk irrespective of where located are apt to clog.

A liquid conveying conduit 17 extends through the connecting-means 18 of the connecting portion 9 above the connected end of the handle-portion 11, through a portion of said connecting-portion 9 and through the nozzle-portion 10 up to the orifices 16 and it may also have the orifice at the free end of the nozzle 10. This conduit 17 is provided with means 18 for connecting to the flexible tubular conduit 5 and is directed generally in the same direction as the handle-portion 11.

For vaginal therapy, the connecting-portion 9 is provided preferably with a nozzle as illustrated in Figs. 2 and 3. The improvement in this nozzle resides in that it is provided with a plurality of ridges 19 formed on the core thereof extending radially spaced apart from the free end thereof to a point adjacent the flared connecting end thereof and with a plurality of channels 20 extending between the ridges 19. The ridges 19 are sufficiently projected to distend the vagina for effective therapy and the channels 20 are sufficiently deep to convey the liquid stream discharged by the nozzle-portion 10. This nozzle-portion has the connecting end thereof flared to form an annular neck between the ends 21 of the ridges 19 and said flared end adapted to be engaged by the vaginal sphincter. Orifices 22 may be formed to communicate with the channels 20 and

one may be formed in the free end of said nozzle-portion.

What I claim is:

1. In a colonic-vaginal irrigator for use in combination with a flexible tubular conduit connected to a liquid supply, a body-portion of suitable material embodying an intermediate connecting-portion, a nozzle-portion and a handle-portion, said body-portion having a conduit extending longitudinally through the nozzle-portion and through a portion of the connecting portion emerging in the side of said connecting-portion in the form of a means adapted for connection to the flexible tubular conduit, said connecting-portion and said handle-portion having a juncture in the form of a depending nubbin adapted to prevent flush ascending the handle-portion and to drain said flush down along the surface of said nubbin.

2. The structure as set forth in claim 1, in which, the nozzle including the core and the ridges on said core, have a diameter of at least an inch and a quarter.

3. The structure as set forth in claim 1, in which, the nozzle-portion has an annularly flared connecting end-portion and an annular bulge spaced apart from said flared connecting end-portion so as to form an annular neck adapted to be engaged by a sphincter.

4. The structure as set forth in claim 1, in which, the nozzle-portion embodies a tubular core, an annularly flared connecting end-portion, and at least five radially spaced apart ridges formed on the core of said nozzle-portion, extending from the free end of said nozzle-portion to the proximity of the flared connecting end-portion, curving down to the core of said nozzle-portion, collectively to form an annular neck between the flared end-portion and the curved down ends of said ridges, adapted to be engaged by a sphincter.

5. The structure as set forth in claim 1, in which, the nozzle-portion embodies a tubular core, an annularly flared connecting end-portion, and at least five radially spaced apart ridges formed on the core of said nozzle portion, extending from the free end of said nozzle-portion to the proximity of the flared connecting end-portion, curving down to the core of said nozzle-portion, collectively to form an annular neck be-

tween the flared end-portion and the curved down ends of said ridges, adapted to be engaged by a sphincter, said nozzle-portion, including the core and the ridges on said core, having a diameter of at least an inch and a quarter.

6. The structure as set forth in claim 1, in which, the nozzle-portion has a flared connecting end-portion and an annular bulge in proximity to the flared connecting end-portion to form an annular neck adapted to be engaged by a sphincter, and in which, said nozzle-portion has a clavate free end-portion of maximum girth in proximity to the free end thereof and outlet orifices countersunk in the lateral surface of said maximum girth.

7. A colonic-vaginal nozzle embodying a body-portion including a connecting end-portion annularly flared at the connecting end and annularly bulged in proximity to the flared end so as to form an annular neck adapted to be engaged by a sphincter; and a clavate free end-portion having a maximum girth in proximity to the free end thereof, and outlet orifices counter-sunk in the lateral surface of said maximum girth.

8. A colonic-vaginal nozzle embodying a body-portion including a tubular core, an annularly flared connecting end-portion and at least five radially spaced apart ridges formed on the core of said nozzle and extending from the free end of said body-portion to the proximity of the annularly flared end-portion curving down to said core collectively to form an annular neck between the flared end-portion and the curved down ends of said ridges, adapted to be engaged by a sphincter.

35 EDWARD SOKOLIK.
